TOY BAT

Samuel F. Speers, 120 Mount Hope St.,
North Attleboro, Mass. 02703

Filed Oct. 1, 1973, Ser. No. 402,615

Term of patent 3½ years

Int. Cl. D21—01

U.S. Cl. D34—5 BC

FIG. 1

FIG. 2

FIG. 3

FIG. 4

FIG. 5

FIG. 1 is a side elevational view of a toy bat showing my new design;

FIG. 2 is a top plan view thereof;

FIG. 3 is a bottom plan view thereof;

FIG. 4 is an end view, looking from the left with respect to FIG. 1; and

FIG. 5 is an end view, looking from the right with respect to FIG. 1.

The drawing is shaded for yellow.

I claim:

The ornamental design for a toy bat, substantially as shown and described.
